UNITED STATES PATENT OFFICE.

JOSEF R. CAMBERN, OF SPOKANE, WASHINGTON, ASSIGNOR TO CAMBERN CORPORATION, OF SPOKANE, WASHINGTON.

DESIGN FOR A DUTCH SHOP.

Application filed March 29, 1929. Serial No. 30,676. Term of patent 14 years.

To all whom it may concern:

Be it known that I, JOSEF R. CAMBERN, a citizen of the United States of America, residing at Spokane, in the county of Spokane and State of Washington, have invented a new, original, and ornamental Design for Dutch Shops, of which the following is a specification, reference being had to the accompanying drawing, forming a part thereof.

Fig. 1 is a front elevation of a Dutch shop showing my new design.

Fig. 2 is an end elevation.

I claim:—

The ornamental design for a Dutch shop, as shown.

JOSEF R. CAMBERN.
